UNITED STATES PATENT OFFICE.

ADDISON BOREN, OF PITTSBURG, PENNSYLVANIA.

DUST-GUARD FOR AXLE-BOXES.

SPECIFICATION forming part of Letters Patent No. 740,621, dated October 6, 1903.

Application filed November 19, 1902. Serial No. 131,932. (No model.)

To all whom it may concern:

Be it known that I, ADDISON BOREN, a resident of Pittsburgh, in the county of Allegheny and State of Pennsylvania, have invented a new and useful Improvement in Dust-Guards for Axle-Boxes; and I do hereby declare the following to be a full, clear, and exact description thereof.

My invention relates to dust-guards for axle-boxes, its object being to provide a simple form of guard which will effectively act to exclude the dust from the axle-box, as well as prevent the escape of lubricant, and at the same time one which is simple in construction and which may be manufactured at small cost.

To these ends my invention comprises, generally stated, in conjunction with an axle-box of the ordinary construction, a dust-guard consisting of an outer casing having outwardly-extending flanges along its outer edges and an opening for the passage of the axle, together with an inner casing having inwardly-extending flanges adapted to enter said metallic frame and suitable packing material interposed between the flanges of said frame and casing and projecting beyond same, whereby a very strong and simple construction is obtained, with the packing material so arranged as to be securely held in place and to effectively exclude the dust from the axle-box.

In the accompanying drawings, Figure 1 represents a sectional view of an axle-box with my invention applied thereto. Fig. 2 is a view of the dust-guard removed and shown half in section, and Fig. 3 is a vertical section of my improved dust-guard.

Like numerals indicate like parts.

The axle-box 2 may be of the ordinary construction, having the ordinary bearings 3 and 40 the door 4. At the rear of the box 2 is the seat or guideway 5 for the reception of the dust-guard.

My improved dust-guard consists of the box-like frame made up of outer-casing 6, having 45 the outwardly-extending flanges 7 surrounding said casing at its edges and having the opening 8, through which the axle 9 may pass. Within the frame 6 is the inner casing 10, which has the inwardly-projecting flanges 11 and the vertical flanges 12. The casing 10 has also the opening 13 for the passage of the axle 9. The casing 10 is adapted to fit with-

in the outer casing 6, space being left between the outwardly-extending flanges 7 of the casing 6 and the inwardly-extending flanges 11 of the casing 10. Into this space so formed the packing 14 is inserted, said packing being formed of leather or any other suitable material. The packing is forced or driven down into the space between the flanges 7 and 11, so as to fit tightly therein, and further means may be employed, if necessary, to secure said packing in place. The said packing 14 projects slightly beyond the flanges of the casing 6 and casing 10, so that when the guard is inserted into the seat 5 of the axle-box the packing will press closely against the inner walls of said seat, so as to form a very effective and close joint to prevent the entrance of dust, cinders, &c., and the escape of the lubricant. The packing 14 further acts to hold the frame of the dust-guard snugly within the seat 5, so that said frame does not partake of any movement caused by the play of the axle, which is taken up by the movable bearing-blocks about to be described.

Bearing-blocks 15 16 are contained within the casings 6 and 10, said blocks being acted on by the springs 17, inserted in the upper and lower ends of the casing 10, the action 80 of said springs being such as to force the bearing-blocks into contact with the axle 9. Leather or other suitable packing material 18 is carried by the bearing-blocks 15 16, said packing surrounding the axle and bearing 85 closely thereon owing to the action of the springs 17. The bearing-blocks 15 16 are constructed so as not to completely encircle the axle, the space 19 being left to allow for wear, this wear being taken up by the action 90 of the springs 17, so that the packing material 18 is always held in contact with the axle.

By the use of the flange 12 the casing 10 is held securely within the casing 6, and no fastening means is necessary, as the packing 14 bears directly on the flange 12 and acts to hold the casing 10 securely in position within the casing 6.

A portion of the casing 10 is cut away, as at 20, so as to permit the return to the axle-box of any oil carried by the axle into the dust-guard. This oil will naturally be carried to the lower end of the dust-guard, and by the cutting away of the casing at 20 this

oil is permitted to return to the axle-box, thereby preventing the waste of the oil. A portion of the lower bearing-block is beveled off, as at 21, so that the movement of said block will tend to force any oil collected in the casing back into the axle-box.

If the lower bearing-block were not beveled in the manner described, the jarring action of the bearing-block would tend to cause the oil 10 to seep in both directions and allow it to escape inwardly or away from the axle-box. By having the bearing-block beveled in the manner described the jarring action of the block will tend to force the oil back into the 15 axle-box, while the opening 20 permits the oil to find its way back into the axle-box.

To further aid in preventing the escape of the lubricant, the lower edges of the casing 20 may be provided with felt or other suitable 25 packing 22.

When my improved dust-guard is in use and is inserted in the seat in the axle-box, it remains stationary therein, with its packing 25 pressing against the walls of said seat to prevent the entrance of dust, &c., or the escape of the lubricating material. While the frame of my dust-guard remains fixed in its seat the bearing-blocks have sufficient movement with 30 relation to each other to provide for wear or for the play of the axle.

A dust-guard constructed in accordance with my invention is very simple in construction, being composed of few parts and readily removable, while at the same time it will act 25 to effectively prevent the entrance of dust to the box and at the same time reduce the waste of oil.

What I claim as my invention, and desire to secure by Letters Patent, is—

1. A dust-guard comprising an outer casing 40 having outwardly-projecting flanges, an inner casing entering said outer casing and having inwardly-projecting flanges, and packing material inserted between the flanges of said casings and extending beyond said casings. 45

2. A dust-guard comprising an outer casing having outwardly-extending flanges, an inner casing having inwardly and vertically extending flanges within said outer casing, and packing interposed between the outwardly 50 and inwardly extending flanges and extending beyond said casings.

3. The combination with an axle-box having a seat therein, of a dust-guard comprising an outer casing, an inner casing within 55 said outer casing, packing material interposed between said casings, the lower portion of said inner casing being cut away to form an outlet to said axle-box.

4. The combination with an axle-box having a seat therein, of a dust-guard comprising an outer casing, an inner casing within 60 said outer casing, packing material interposed between said casings, bearing-blocks within said casings, the one movable with relation to the other, the lower bearing-block being beveled, and said inner casing being 65 cut away to form an outlet to said axle-box.

In testimony whereof I, the said ADDISON BOREN, have hereunto set my hand.

ADDISON BOREN.
